UNITED STATES PATENT OFFICE.

EDWARD SCHWARTZ, OF CHICAGO, ILLINOIS.

DESIGN FOR AN ELECTRIC HAIR-SINGER.

41,898.

Specification for Design.

Patented Nov. 7, 1911.

Application filed August 10, 1911. Serial No. 643,446. Term of patent 7 years.

To all whom it may concern:

Be it known that I, EDWARD SCHWARTZ, a citizen of the United States, residing at Chicago, in the county of Cook and State of Illinois, have invented a new, original, and ornamental Design for an Electric Hair-Singer, of which the following is a specification, reference being had to the accompanying drawing, forming a part thereof.

In the drawing, Figure 1 is a side elevation of the hair singer showing my design; Fig. 2 is an end view from the top; Fig. 3 is an end view from the bottom.

What I claim is:

The ornamental design for an electric hair singer, as shown.

In testimony whereof I have signed my name to this specification, in the presence of two subscribing witnesses, on this 7th day of August A. D. 1911.

EDWARD SCHWARTZ.
